Primary Examiner — Rebecca Tsehay(74) *Attorney, Agent, or Firm* — Oblon, McClelland, Maier & Neustadt, L.L.P.(57) **CLAIM**

The ornamental design for an aerosol generating device, as shown and described.

DESCRIPTION

FIG. 1 is a front, top, and left side perspective view of an aerosol generating device showing the new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof;

FIG. 7 is a left side elevational view thereof; and,

FIG. 8 is a front and top perspective view thereof.

1 Claim, 8 Drawing Sheets(56)
